UNITED STATES PATENT OFFICE.

CARL JACOBSON, OF HAMBURG, NEW YORK.

HOISTING-BUCKET.

1,187,626.

Specification of Letters Patent. Patented June 20, 1916.

Application filed July 14, 1914. Serial No. 850,946.

To all whom it may concern:

Be it known that I, CARL JACOBSON, a citizen of the United States, residing at Hamburg, in the county of Erie and State of New York, have invented new and useful Improvements in Hoisting-Buckets, of which the following is a specification.

This invention relates to the class of clam-shell buckets employed more particularly for hoisting ore in loading and unloading railway cars and vessels and comprising a pair of shells or scoops pivoted to suitable tackle which is constructed to draw them tightly together while hoisting and transferring the load.

The object of my invention is to improve the construction of such buckets with a view of materially increasing their durability.

In the accompanying drawings: Figure 1 is a side elevation of a hoisting bucket embodying the invention. Fig. 2 is a perspective view of one of the bucket-shells. Fig. 3 is a similar view showing the bucket-bottom adjusted for wear, preparatory to cutting away its projecting front portions. Fig. 4 is an enlarged horizontal section on line 4—4, Fig. 1, omitting some of the rivets.

Similar characters of reference indicate corresponding parts throughout the several views.

1 indicates the scoops or shells of the bucket which are pivotally attached to any suitable or well known hoisting tackle. This tackle is not shown in the drawings, as it forms no part of my invention.

Each of the bucket-shells comprises a pair of upright side walls 2 and a bottom or bottom-plate 3 provided at its side edges with upturned flanges 4 which are secured to the side walls by rivets 5 or other suitable fastenings. This bottom is preferably cast of manganese steel, but may be constructed of any other suitable material. The shells are open at their rear as well as their front ends, and their front edges are reduced or sharpened, as usual, to readily cut through the material in picking up a load, the sharpened edges closing against each other to retain the load in the bucket while transferring it, in a well known manner.

The front edges of the shell-bottoms wear away rapidly, permitting leakage of the material between them, and with one-piece shells as ordinarily constructed, when such wear and leakage become excessive, it is necessary to discard the entire bucket. To

enable such wear to be taken up and prolong the life of the bucket, I make the bottom longitudinally adjustable on the side walls of the shell and also make it reversible thereon end for end. For this purpose, as regards the longitudinal adjustment of the bottom, the rivet holes 6 and 7 formed respectively in the side walls and the bottom flanges 4 are spaced symmetrically, so that when the front edge of the bottom becomes unduly worn, it may be shifted forward on the side-walls the distance from one rivet hole to the next, as shown in Fig. 3, this being done by cutting off the rivets, shifting the bottom and then again riveting it to the side-walls. After thus adjusting the bottom, the projecting front portions 8 of its flanges are cut off flush with the front edges of the side walls, to permit the front edges of the two shells to meet and close tightly, as before, this cut being indicated by the dotted line 8^a. This adjustment of the bucket-shell practically doubles its life. In the preferred construction illustrated in the drawings, each bottom flange is secured to the contiguous side-wall by two rows of rivets, and the rivet-holes in the side-walls are twice as numerous as those in the bottom-flanges.

To still further increase the durability of the bucket, the bottom of each of its shells may be reversed end for end, as before stated. For this purpose, the front and rear edges of the bottoms are sharpened or constructed symmetrically, both of said edges being plain or unflanged, so that either may readily penetrate the mass of material to be hoisted. After the bottom has been adjusted longitudinally, as hereinbefore described, it may be reversed by cutting the rivets and re-riveting it in reversed position to the side-walls, both ends of the bottom being constructed to bear squarely against the end of the opposing scoop to form a closed joint between the scoops in both of the reversed positions of the bottom. After such reversal, the bucket may be again used for a considerable time; and when this new front edge becomes worn to an excessive depth, the reversed bottom may be again adjusted forwardly, as before, the bucket being serviceable for a considerable period after each adjustment and reversal.

By this construction, the durability of the bucket-shells is practically four times that of an ordinary shell in which the bottom and side walls are integral and which must be

wholly renewed when the cutting edge of the bottom becomes unduly worn. Such buckets are comparatively large and the cost of their two shells is approximately six hundred dollars. It is manifest therefore that in quadrupling the life of the bucket, my invention effects the important saving of about seventy-five per cent. in the cost of this part of the hoisting and transferring equipment.

As shown, the bottoms of the shells may be provided in their corners with suitable fillets or reinforcements 9. The flat upper edges of these fillets are arranged closely to the straight lower edges of the side walls 2. In the preferred construction shown in the drawings, the bottoms of the shells slope forwardly or toward each other, and the upper edges of said fillets and the lower edges of the side walls are inclined and substantially parallel with said bottoms. This relative arrangement of the parts permits the bottoms to be reversed, as hereinbefore described, and to slope toward each other in either of their reversed positions.

I claim as my invention:

1. A clam-shell bucket having scoops, each comprising side walls, a separate bottom having upturned side-flanges, and means for securing the bottom-flanges to the side walls, the bottom being reversible end for end on the side walls and having symmetrical front and rear edges both of which are unflanged to penetrate the mass of material to be hoisted and constructed to bear squarely against the opposing end of the other scoop to form a closed joint between the scoops in both of the reversed positions of the scoop-bottoms.

2. A clam-shell bucket having scoops, each comprising side walls and a separate bottom having integral upturned side flanges, the bottom being reversible end for end on the side walls and having symmetrical front and rear edges both of which are unflanged and constructed to bear squarely against the opposing end of the other scoop to form a closed joint between the scoops in both of the reversed positions of the scoop-bottoms, said side-walls and bottom flanges having longitudinal rows of symmetrically-spaced holes adapted to receive fastenings for securing the bottom in different longitudinal adjustments on said walls in both of its reversed positions.

3. A clam-shell bucket having scoops, each comprising side-walls and a forwardly-inclined bottom adapted to be reversed end for end on said walls, the bottom having integral upturned side-flanges secured to the side-walls and fillets located adjacent to the lower edges of the side-walls, the upper edges of the fillets and the lower edges of the side-walls being substantially parallel with the inclined bottom, whereby the latter slopes toward its front edge in either of its reversed positions, both ends of the bottom being constructed to bear squarely against the opposing end of the other scoop to form a closed joint between the scoops in both of the reversed positions of the scoop-bottoms.

Witness my hand this 8th day of July, 1914.

CARL JACOBSON.
